UNITED STATES PATENT OFFICE

148,359

DESIGN FOR A COMBINED HOLDER FOR
PICTURE AND PERFUME CONTAINERS

John Joelson, New York, N. Y.

Application March 6, 1946, Serial No. 127,160

Term of patent 3½ years

(Cl. D29—20)

To all whom it may concern:

Be it known that I, John Joelson, a citizen of the United States, residing at New York, in the county and State of New York, have invented a new, original, and ornamental Design for a Combined Holder for Picture and Perfume Containers, of which the following is a specification, reference being had to the accompanying drawing, forming part thereof.

Fig. 1 is a perspective view of a combined holder for picture and perfume containers, showing my new design; and

Fig. 2 is a central, vertical cross section through Fig. 1, with the perfume container omitted.

The dominant feature of the present design resides in the portions shown in full lines.

I claim:

The ornamental design for a combined holder for picture and perfume containers, as shown and described.

JOHN JOELSON.
